UNITED STATES PATENT OFFICE.

JAMES G. NORTON, OF ELTINGVILLE, NEW YORK, ASSIGNOR TO UNITED SHOE MACHINERY CORPORATION, OF PATERSON, NEW JERSEY, A CORPORATION OF NEW JERSEY.

SKIVING MACHINE.

Continuation of application Serial No. 274,042, filed January 30, 1919. This application filed December 4, 1920. Serial No. 428,260.

To all whom it may concern:

Be it known that I, JAMES G. NORTON, a citizen of the United States, residing at Eltingville, S. I., in the county of Richmond 5 and State of New York, have invented certain Improvements in Skiving Machines, of which the following description, in connection with the accompanying drawings, is a specification, like reference characters on the 10 drawings indicating like parts in the several figures.

This invention relates to machines for operating upon stock and is herein illustrated as embodied in a machine for evening soles, 15 heel lifts and similar articles which are used in the manufacture of boots and shoes.

In application Ser. No. 274,042, filed in my name, there is disclosed a method of grading heel lifts and similar articles which comprises, in one of its aspects, sorting the lifts 20 into groups the individual members of which have the same thickness-difference, that is, the same difference in thickness between their thickest and their thinnest localities, 25 and then running the members of each group through an evening machine which is set, once for each group, so that it will remove from each lift a skiving the maximum thickness of which is equal to the thickness-difference of the lift. In this way there is produced from each heel lift blank, irrespective 30 of its average thickness as well as of its thickness-difference, a lift of the greatest possible uniform thickness.

The general object of the present invention is to provide a machine of this type. According to one feature of the invention the machine has a cutter and two members for directing one by one a series of blanks 35 of uneven thickness to the cutter, means being provided for so adjusting and operating the machine that a series of skivings, of uneven thickness each having the same maximum thickness will be removed from the blanks of the series. In the illustrative machine the two members which grip and feed the blanks are respectively a gage member 40 and a feed member. The gage member comprises a plurality of pressers the blank-engaging faces of which lie normally in a common plane and a carrier or block in which these pressers are yieldingly mounted. The feed member comprises a second block or carrier in which a series of feed rolls are

mounted on fixed axes. In the operation of 55 the machine the gage member is adjusted manually into position such that when a blank is forced against its yielding pressers and fed to the knife by the rolls of the feed member, an uneven skiving of the desired 60 maximum thickness will be removed from each blank, said maximum thickness being equal to the thickness-difference of the blank.

This and other features of the invention, including certain details of construction and 65 combinations of parts, will be described as embodied in an illustrative machine and pointed out in the appended claims.

Referring now to the accompanying drawings, 70

Figure 1 is a side elevation of a machine in which the present invention is embodied;

Figure 2 is a front elevation of the machine;

Figure 3 is a perspective of the upper 75 blank-engaging or gage member;

Figure 4 is a perspective of the lower blank-engaging or feed member, and

Figure 5 is a section through the two members showing a blank in process of being skived.

Referring more particularly to Figure 1, there is mounted on a suitable bed formed on the frame of the machine a skiving knife 7 which is held in adjusted position by cap-screws one of which is indicated at 9, adjusting screws, one of which is shown at 11, being provided for adjusting the knife into proper position. The mounting of the knife is old and well known and will not be described further than to explain that slots in the knife, through which the cap screws pass, permit the adjustment.

Located to engage the upper side of a blank 100 is a gage member which is urged 95 upwardly at all times by springs 15 and may be adjusted downwardly by turning a hand wheel 37. Referring now more particularly to Figure 3 with occasional references to Figures 1, 2 and 5, the gage member comprises a carrier in the form of a block 17 having studs 19, one at each of its four corners, to be received by the upper ends of the coiled springs 15. Mounted in suitable vertical guide-ways in the block 17 are a plurality of holders 21 (see Fig. 5); and in each holder is rotatably mounted a presser roll 23. The stem of each holder 21

extends up through a bore in the block 17 and has threaded upon its upper end a nut 25, each stem being encircled by a coiled spring 127 which exerts at all times a force 5 to push its respective carrier 21 and roll 23 downwardly. The nuts 25 limit such downward movement and are so adjusted that, when no blank is being engaged, the lower elements of the rolls 23 lie in a common 10 horizontal plane. Extending upwardly from the block 17 are two slides 27 which are located in suitable guideways formed in the frame of the machine and held in place by plates 29. The upper ends of the 15 slides 27 are beveled as shown and are engaged by wedges 31 formed at opposite ends of a horizontal slide-bar 33, said bar having an eye threaded to receive a screw 35 which is held from longitudinal movement 20 but may be rotated by means of the hand wheel 37 which is fast to one end of the screw. The springs 15 hold the beveled upper ends of the slides 27 up against the wedges 31 so that when the hand wheel is 25 turned in one direction the upper blank-engaging member comprising the block 17 and rolls 23 is raised and, when the wheel is turned in the other direction, the blank-engaging member is lowered. In the operation 30 of the machine, as will presently be explained, when a group of blanks are to be operated upon the members of which each have the same thickness-difference, the upper blank-engaging member is set in such 35 position that the distance from the plane of the cut of the knife to the plane which would contain the lower elements of the rolls 23, if said rolls were in their uppermost positions, is equal to the amount of 40 this thickness-difference. In order to facilitate the adjustment of the upper blank-engaging member, a pointer 39, pivoted at 45 to a stationary cross-bar 43 and having a forked lower end which embraces a pin 45 on the slide-bar 33, co-operates with a scale 46 mounted on the cross-bar. The thickness of soles, heel lifts etc. is commonly measured in "irons" and fractions thereof, an "iron" being one forty-eighth 50 of an inch; and the scale and pointer are constructed and arranged to indicate distance in irons from the plane of the cut of the knife to the plane of the lower elements of the rolls 23 when said rolls are in their 55 uppermost positions. Consequently, if the thickness-difference of the member of any given group of blanks is known, all the operator has to do, in order to set the machine for skiving those blanks, is to turn the hand-wheel until the pointer and scale indicate the amount of that thickness-difference.

The lower blank-engaging member, which for convenience will be referred to as the feed member, comprises a block 47 having 60 unyieldingly mounted therein a plurality of

rolls 49 which are rotated continuously in a counter-clockwise direction, as viewed in Fig. 5, so as to feed the blank to the knife. The block 47 has depending from its under side a generally U-shaped slide 51, the upright arms of which are slidable in suitable guideways formed in the frame of the machine. Extending vertically between the horizontal portion or base of the U-shaped member 51 and the block 47 and integral with the block and member is a cylindrical brace 53 in which is mounted a heavy spring 55 and a plunger 57, there being driven into the plunger a pin 59 which extends into a slot formed in the cylindrical brace. When a blank is being fed into position between the upper and the lower blank-engaging members, the lower member is in lowered position as shown in Fig. 1; but before the forward edge of the blank reaches the knife, the lower member is raised so as to grip the blank between the two members and hold it so gripped during the skiving operation, this latter position of parts being shown in Fig. 5. 90

The raising and lowering of the lower blank-engaging members is effected through the plunger 57. The lower end of this plunger is formed with two eyes to receive a pivot pin 61 which also passes through a bore in the upper end of the upper lever 63 of a toggle, the lower end of said upper lever being pivoted at 65 to the upper end of a lower lever 67, said lower lever having a hub in the form of a sleeve 71. This sleeve is pinned at 73 to a rock-shaft 75 to the outer end of which is pinned a crank-arm 77, the construction being such that when the crank-arm is oscillated the toggle will be alternately straightened to 105 raise the lower blank-engaging member and broken to permit it to fall. Pivoted to the crank-arm at 79 is a connecting-rod 81 having at its upper end a substantially square opening to receive a cam 82 which is fast to the shaft 83 to which a driving pulley 85 is fast. Rotation of the pulley will therefore raise and lower the connecting-rod 81 and, through the toggle mechanism, effect raising and lowering of the 110 lower blank-engaging member.

The group of blanks, each of which has the same thickness-difference, is placed in superposed relation in a magazine 85, which may be of any approved construction. In order to feed the blanks one by one from the magazine, a feed slide 87 is provided, having on its under side a rack adapted to be actuated by a toothed sector 89 formed upon the upper end of an arm 91. This arm is fast to the middle of a rock-shaft 93 to one end of which is pinned an arm 95. A rod 97 is pivoted at one end to the arm 95 and at the other to the connecting rod 81. 120

Referring again to the cam 82 as it appears in Fig. 1, noting that it moves in the direction indicated by the arrow and that its upper face 98 (in the position shown) is struck on a radius about the axis of the shaft 83, its effect upon the feed slide and upon the lower blank-engaging member is as follows: In the position shown, it has raised the connecting-rod 81, with consequent lowering of the lower blank-engaging member, and is holding it raised. At the same time, it has swung the connecting-rod part way toward the left and has consequently partially fed a blank into place between the blank engaging members. It is the leading corner 99 of the cam which causes the various movements of the connecting rod 81. In the position shown, as has been explained, this corner is swinging the rod to the left and consequently causing the feeding of a blank while the radial face 98 is maintaining the connecting rod raised and consequently the lower blank-engaging member in lowered position. As the cam continues its rotation, the feeding of the blank is completed, the radial face 98 holding the connecting-rod 81 raised. Next the leading corner 99 pushes the connecting-rod downwardly thereby raising the lower blank-engaging member to press the blank against the rolls 23 the radial face 98 holding the connecting-rod to the left. The leading corner 99 then swings the connecting-rod to the right, thus returning the feed slide to its initial position, the radial face 98 during this movement serving to hold the connecting-rod in lowered position and consequently the lower blank-engaging member in raised position while the skiving operation is taking place. The leading corner 99 next moves the connecting rod upwardly thereby lowering the lower blank-engaging member into the position shown, the radial face 98 maintaining the feed slide in its right-hand position during this movement. Thereafter the leading corner 99 starts the feeding of a succeeding blank while the lower blank-engaging member is held in its lowered position. This completes the cycle which is repeated as long as the pulley 85 is rotated.

The operation of the cam 82 has been described for convenience through one complete cycle without reference to certain mechanism for locking the lower blank-engaging member. After the blank has been fed into position to be skived and the lower blank-engaging member has been raised to grip and feed it, it is desirable that said member be locked firmly in its raised position, held rigidity against movement either toward or away from the knife until the skiving has been completed, and thereafter released so that it may drop into its lowered position. In order to lock the lower blank-

engaging member from downward movement during the cutting operation, there are formed in the walls of the guideways in which the upright arms 51 are vertically slidable, pockets 20 having downwardly inclined outer walls, and in each pocket is located a roller 22. With the construction thus far described it will be clear that the lower blank-engaging member may be freely raised but that the rollers 22 will lock it against being lowered until they are pushed upwardly in their pockets. Extending up into each pocket is a rod 24, the lower end of which is adapted to be engaged by a tappet 26, the stem of which is threaded into the outer end of a lever 28 which is pivoted to the frame of the machine at 30. The inner ends of the two levers 28 are received in a groove formed in a collar which is part of the plunger 57. When the plunger, and consequently the lower blank-engaging member is in lowered position, as shown, the rollers 22 rest upon the upper ends of the rods 24. When, however, the plunger moves upwardly, the outer ends of the levers 28 move downwardly, thus permitting the upper ends of the rods 24 to be withdrawn from the pockets 20. Under these conditions the rollers 22 form one-way locks which prevent the lower blank-engaging member from moving downwardly; and consequently said member remains locked from downward movement in any position to which it is raised until the plunger 57 is moved downwardly whereupon the rods 24 are projected upwardly to free the rollers 22 and permit the lower blank-engaging member to fall. In order to lock the lower blank-engaging member from upward movement during the cutting operation there are pivoted in slots in the upright slides 51 of the lower blank-engaging member two eccentric friction pawls 40, the operative faces of which are arranged to engage at the proper time outer walls 42 of the guideways in the frame of the machine in which the slides 51 are mounted. Through a perforation in the tail of each pawl passes loosely the upper end of a rod 44, the lower ends of these rods being pivoted respectively to the arms 28. Springs 48 encircle the rods; and adjusting nuts 50, by turning which the angular positions of the pawls may be varied, are threaded upon the upper ends of the rods above the tails of the eccentric pawls. In the position of parts shown in the figures, the lower blank-engaging member 47 is in its lowered position. Considering now the upward movement of the plunger 57, which is produced by the straightening of the toggle levers 63, 67, this movement may be considered to take place in two stages. In the first stage the blank-engaging member is raised until it presses the blank 100 firmly up against the rolls 23 of the upper blank-engaging mem-

ber. In the second stage, which is much the shorter one, the blank-engaging member 47 remains stationary while the spring 55 is compressed more or less. During the first 5 stage the operative faces of the eccentric pawls 40 are not moved into locking engagement with the walls 42, and consequently there is nothing to prevent the upward movement of the blank-engaging member 47. During the second stage of the upward movement of the plunger 57, however, the pawls 40 are forced into firm engagement with the walls 42, and any further upward movement which the lower blank-engaging member 47 might otherwise make is prevented. The pawls 40 may be timed properly by manipulating the nuts 50.

The lower blank-engaging member is thus held during the skiving operation from upward movement by the pawls 40 and from downward movement by the rollers 22. After the completion of the skiving operation the plunger 57 is pulled downwardly, this downward movement serving first to release the rollers and free the pawls and then to permit the lower blank-engaging member 47 to fall into the position shown.

Referring now more particularly to Figs. 4 and 1, the mechanism for rotating the feed rolls 49 will be described. Five such rolls are shown and, for convenience, they will be referred to as the first to the fifth roll beginning with the forward one which is farthest from the knife. The first, third 35 and fifth rolls have keyed upon their shafts gears 101 while the second and fourth rolls have loosely mounted upon their shafts gears 103, all five gears 101, 103 being of the same size and arranged to mesh one with another. On that end of the shaft of the third roll which is remote from its gear 101 is fast an internal gear 105, and meshing with this gear are two gears 107 which are fast respectively to the shafts of the second and fourth 40 rolls. With this construction, rotation of that gear 101 which is fast to the shaft of the fifth roll will cause all of the rolls to rotate in the same direction. Meshing with this last-named gear 101 is a gear 109 rotatable about a pivot 111 which connects two links 113, 115, the upper end of the link 113 having a bore to receive the shaft of the fifth roll 101, and the rear or left-hand end of the link 115 having a bore to receive the 45 shaft 83. A gear 117, which is fast to the shaft 83, meshes with the gear 109. With this construction it will be seen that the raising and lowering of the lower blank-engaging member does not disturb the mesh 50 of the various gears, and that consequently the rolls 49 are rotated continuously in such a direction as to advance a blank to the knife as soon as they have pushed the blank into firm contact with the rolls 23 of the upper 55 blank-engaging member.

Considering now more in detail the setting and operation of the skiving mechanism, it will be understood that the blanks which are to be skived have previously been sorted into groups each member of which 70 has the same thickness-difference as have the others, although the blanks may differ greatly in their actual or average thicknesses. Blanks of one such group are now placed in the magazine, and the upper blank-engaging member adjusted by means of the hand wheel 16 until the pointer 45 indicates the proper mark on the scale. The machine is then started, the upper blank-engaging member being maintained in its adjusted 75 position until all the blanks of a particular group have been run through the machine. As each blank is fed between the upper and lower blank-engaging members, the lower member is raised yieldingly through the heavy spring 55 until it forces the blank 80 firmly against the rolls 23 of the upper member and is itself locked against movement either toward or from the plane of the cut of the knife. The blank now lies flat upon the upper elements of the feed rolls 49, being held down upon these rolls by the presser rolls 23, the supporting springs 127 of which are strong enough to accomplish 85 such holding. The lower face of the blank 90 is thus held in a horizontal plane which is parallel to the plane of the cut of the knife so that the finished article, which eventually passes beneath the knife, will be of a uniform thickness throughout. The upper face 95 of the blank does not lie in a horizontal plane but in an inclined plane, if the blank is regularly tapered from end to end, or at various levels if there are thick spots separated by thin spots. Assuming, for convenience of explanation, that the blank is thickest at its leading edge and tapers regularly to its following edge, the presser roll 23 nearest the knife will at first be pushed up to the limit of its upward movement so as to 100 be no longer yielding, and the remaining rolls 23 will extend downwardly each more than the preceding one. The chip or skiving removed by the knife in this case will be 105 thicker at the leading end than at the following end, the finished article being of a uniform thickness throughout approximately equal to the distance between the plane of the cut of the knife and the plane of the upper elements of the rolls 49. It should be 110 noted that after the lower blank-engaging member has been pushed up against the blank to grip and feed it to the knife, the distance from the plane of the upper elements of the feed rolls 49 to the lower element of that presser roll 23 which is pushed 115 up to the limit of its upward movement and is therefore pressing rigidly against the blank is equal to the thickness of the thickest locality of the blank. It should also be 120 125 130

noted that by reason of the spring 55, the distance through which the lower blank-engaging member is moved upwardly in any given case depends upon the general or average thickness of the blank which is being operated upon.

The prior application Serial No. 274,042, which has been referred to above, contains claims to a method of treating blanks including evening them, but contains no claims to the machine which is therein shown and briefly described, the present application being a continuation, so far as common subject-matter is concerned, of that application. Prior application Serial No. 415,810 filed in my name, shows and describes a machine for evening one after another blanks which are heterogeneous as to their thickness-differences, the evening mechanism, except that it is automatically set, being similar to the evening mechanism of the present application, and broad claims to said mechanism without reference to its automatic setting appear in said prior application.

Although the invention has been set forth as embodied in a particular machine, it should be understood that the invention is not limited in the scope of its application to the particular machine which has been shown and described.

Having thus described my invention, what I claim as new and desire to secure by Letters Patent of the United States is:

1. A machine of the class described having, in combination, a cutter, a gage member and a feed member for gripping one by one a series of blanks each of which has the same thickness difference and directing them to the cutter, operator controlled means for producing relative adjustment between the gage member and the cutter to space them apart a distance equal to the amount of thickness difference, and means for thereafter moving the feed member toward the gage member to cause each blank to be gripped and fed in such manner that a skiving of uneven thickness and having the same maximum thickness is removed from each blank and passes between the gage member and the cutter.

2. A machine of the class described having, in combination, a cutter, a gage member and a feed member for gripping one by one a series of blanks each of which has the same thickness difference and directing them to the cutter, operator controlled means for producing relative adjustment between the gage member and the cutter to space them apart a distance equal to the amount of thickness difference, and means for thereafter moving the feed member toward the gage member and for locking it in a position determined in each case by the maximum thickness of the particular blank engaged.

3. A machine of the class described having, in combination, a cutter, two members adapted to engage one by one a series of blanks and direct them to the cutter, means for producing relative adjustment between one member and the cutter and for holding said member and cutter against movement of separation in their relatively adjusted position, and means for compelling the other member to move toward and from the relatively adjusted member and cutter once for each blank passed through the machine while maintaining said relative adjustment.

4. A machine of the class described having, in combination, a cutter, two members adapted to engage one by one a series of blanks and direct them to the cutter, means for producing relative adjustment between one member and the cutter and for holding said member and cutter fixed against movement of separation in their relatively adjusted position, and power-operated means for compelling the other member to move toward and from the relatively adjusted member and cutter once for each blank passed through the machine while maintaining said relative adjustment.

5. A machine of the class described having, in combination, a cutter, two members adapted to engage a series of blanks one by one and direct them to the cutter, means for adjusting one member into a desired position with respect to the cutter and for holding it so that it cannot be moved away from the cutter, and means for compelling the other member to move toward and from the adjusted member once for each blank passed through the machine while said adjusted member remains in its adjusted position.

6. A machine of the class described having, in combination, a cutter, two members adapted to engage a series of blanks one by one and direct them to the cutter, means for adjusting one member into a desired position with respect to the cutter and for holding it so that it cannot be moved away from the cutter, and power-operated means for compelling the other member to move toward and from the adjusted member once for each blank passed through the machine while said adjusted member remains in its adjusted position.

7. A machine of the class described having, in combination, a magazine for a stack of blanks, means for feeding the blanks one by one from the magazine, a cutter, two members arranged to receive between them each blank from the magazine and support it during the cutting operation, means whereby relative adjustment between the cutter and one member may be produced to bring said member and cutter into a desired spaced relation, and means acting in timed relation with the feeding means for moving the other

member toward the relatively adjusted member to effect gripping and feeding of each blank and for thereafter moving said other member away from the relatively adjusted member to permit the next blank to be fed between the member, while maintaining the spaced relation between the first-named member and the cutter unchanged.

8. A machine of the class described having, in combination, a cutter, a gage member between which and the cutter the waste skivings pass, a feed member between which and the cutter the finished blanks pass, means for relatively adjusting the gage member and cutter into a given spaced relation and for holding them in said relation, means for alternately lowering and raising the feed member, and means for feeding blanks successively between the members while the feed member is in lowered position.

9. A machine for evening the members of a group of blanks which are heterogeneous in thickness but have the same thickness-difference having in combination, a cutter, two blank-engaging members for directing the blanks one by one to the cutter, means whereby one member and the cutter may be relatively adjusted in accordance with the thickness-difference of the blanks and held in such adjustment against movement of separation, and means for repeatedly compelling relative movement of approach and separation between the adjusted cutter and member and the other member once for each blank operated upon.

10. A machine for evening the members of a group of blanks which are heterogeneous in thickness but of the same thickness-difference having in combination a cutter, two blank-engaging members for directing the blanks to the cutter, means for adjusting one of said members into such position that its blank-engaging face is spaced from the cutter a distance equal to the amount of thickness-difference of the blanks and for holding it set in such position, means for feeding blanks one by one between the members and means for moving the other member toward the adjusted member to grip each blank during the skiving operation and away from the adjusted member in time to permit a succeeding blank to be fed between the members.

11. A machine of the class described having, in combination, a cutter, two members for advancing a blank to the cutter, manually controlled means for adjusting one member in a direction transverse to the plane of the cut and for holding it in adjusted position against movement away from the cutter until a subsequent manual adjustment is made, means for feeding blanks one by one between the members, and means for moving the other member toward the adjusted member to press each blank against

the adjusted member during the cutting operation and for thereafter moving said other member away from the adjusted member to permit a succeeding blank to be fed between the members while maintaining the adjusted member in its adjusted position.

12. A machine of the class described having, in combination, a cutter for removing skivings from a series of blanks, a gage member, means for holding the gage member in a fixed relation to the cutter, a feed member which is at times spaced from the gage member a distance greater than the thickness of the thickest blank to be operated upon, and means for compelling the feed member to move toward and from the gage member once for each blank passed through the machine while maintaining the fixed relation of the gage member and the cutter.

13. A machine for skiving a blank of uneven thickness the thickness-difference of which is known having, in combination, a cutter, two blank-engaging members, means whereby relative adjustment between one member and the cutter may be produced, means for indicating when in such adjustment the said member and cutter are so spaced that the skiving which will be removed will have a maximum thickness equal to the thickness-difference of the blank and means for operating the other blank-engaging member in such manner as to cause the blank to be evened by the removal of the aforementioned skiving.

14. A machine of the class described having, in combination, a cutter, two members for gripping one by one a series of blanks each of which has the same thickness difference and directing them to the cutter, operator-controlled means adapted to be manipulated once for the whole series for producing relative adjustment between one member and the cutter to space them apart a distance equal to the amount of the thickness difference, and means for thereafter moving the other member toward the first-named member and for locking it in a position determined in each case by the thickness of the particular blank which is passing through the machine.

15. A machine for evening a series of blanks the members of which have the same thickness difference by removing from each blank a skiving the maximum thickness of which is in each case the same having, in combination, a magazine for the blanks, a cutter, a gage member and a feed member located between the magazine and the cutter, operator-controlled means for adjusting the gage member to and holding it during the evening of the whole series of blanks in a position spaced from the cutter a distance equal to the thickness difference, means for advancing a blank into a position between

the gage member and feed member, means for moving the feed member toward the gage member to cause the blank to be gripped and fed to the knife, and means for locking the feed member once for each blank in a position determined by the thickness of the particular blank which is passing through the machine.

16. A machine for evening a blank of uneven thickness, the thickness difference of which is known, having, in combination, a cutter, a gage member comprising a base and a plurality of rolls yieldingly mounted therein located at one side of the plane of the cut and in advance of the cutter and some in advance of others with respect to the cutter, a feed member comprising a base and a plurality of unyielding rolls located at the other side of the plane of the cut in advance of the cutter and some in advance of others with respect to the cutter, operator-controlled means for adjusting the gage member and cutter relatively, means for indicating when in such adjustment the gage member and cutter are so spaced that the skiving which will be removed will have a maximum thickness equal to the thickness-difference, and means for operating the feed

member in such manner as to cause the blank to be evened by the removal of the aforementioned skiving.

17. A machine for evening a series of blanks which are heterogeneous as to thickness but have each the same known thickness-difference, having, in combination, a cutter, a gage member comprising a base and a plurality of rolls yieldingly mounted therein located at one side of the plane of the cut in front of the cutter and some in front of others, a feed member comprising a base and a plurality of rolls unyieldingly mounted therein located on the other side of the plane of the cut in front of the cutter and some in front of others, means for producing relative adjustment between the gage member and the cutter in accordance with the known thickness-difference and for maintaining the adjustment during the evening of the series, and means for moving the feed member toward and from the gage member once for each blank passed through the machine.

In testimony whereof I have signed my name to this specification.

JAMES G. NORTON.
